CLAIM

The ornamental design for a sock with zippered pocket, as shown and described.

DESCRIPTION

FIG. 1 is a side perspective view of a sock with zippered pocket, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view taken along line 8-8 of FIG. 4;

FIG. 9 is an inside-out view thereof; and,

FIG. 10 is a left side elevation view thereof, showing the interior of the pocket with the zipper in an open condition. The evenly-dashed broken lines on claimed surfaces depict surface ornamentation applied to the article and form no part of the claim.

The evenly-dashed lines in FIG. 8 depict the cut line and form no part of the claim.

In FIGS. 6, 8, 9 and 10, the pocket of the article is shown with a first-density stippling pattern. In FIGS. 1-4, 7, 8 and 10, the zipper portion of the article is shown with a second-density stippling pattern. The external surface of the sock is shown throughout the figures with a lack of stippling. These distinctions in stippling represent a claimed surface contrast between the zipper, the pocket, and the external surface of the sock.
